ABSTRACT: The present invention relates to a machine for perforating, in the transverse direction, paper webs, such as toilet paper and household paper, and webs of similar material. The main object of the invention is to provide a machine which is simple and safe in its construction and which operates at a very high accuracy and further ensures a perforation without causing any noticeable wearing of the parts of the machine involved in the perforation. The object aimed at has been achieved by shaping the abutment means of a longitudinal border reaching into the movement path of the knives and outside the periphery of the roller, and an elongated pad extending parallel to the roller axis, said pad at the side turned towards the roller provided with abutment and sliding surfaces, for the knife which are extending in the transverse direction of the pad, said surface arranged with some distance from each other and adapted to rebound when being hit by the knife.

PERFORATION MACHINES

Toilet and household paper is practically always provided with a transverse perforation to facilitate the tearing off of the paper pieces. This perforation was previously provided as a so-called stitch perforations the paper thereat being moved between two rollers one provided with one or several longitudinal grooves and the opposite one having projecting tooth knife ribs having equally spaced cuts. The knife roller and the notch roller were coupled to gears and dimensioned in such a way that the knives projected down into the notches in the other roller at rotation.

Nowadays the perforation is performed commonly as a so-called knife perforation for the reason that this kind of perforation is more aesthetic. This perforation is provided by means of a rotating pair of shears. Such a device comprises a strong rotating roller having a number of projecting knife-blades which usually are somewhat helically arranged along the roller and a likewise strong but stationary upper bar having an adjustable knife comprising a number of sections in order to facilitate the adjustment. This device gives a good perforation result if only it is carried out with sufficient stability and freedom of vibration and is extremely well adjusted. In comparison with the device for stitch perforation the machine costs will be very high due to the greater precision and the weight of the machine.

The knife perforation could also be performed by means of a perforation machine (cf. e.g. the Swedish Pat. No. 31 939) which comprises a rotated knife roller and a driven counter roller cooperating with the first roller and being rotated with the same speed, the counter roller being provided with peripheral grooves in the mantle surface. The knife roller is displaced axially back and forth during the rotation. When the paper web passes between the two rollers, the knives make cuts in that parts of the web which are not situated in front of the grooves in the counter roller. A drawback in this kind of a perforation machine is to be seen therein that it must work with a very high grade accuracy as otherwise the knives will cut into the counter roller and damage the same or there will not be obtained any perforation lines at all.

One object of the present invention is to render possible a perfect transverse perforation by means of simpler devices and without any notable precision. The invention relates not particularly to machines for transverse perforation of paper webs and similar material webs, these machines being of the kind having a rotation knife roller with one or several knives extending in the longitudinal direction of the roller, said knives cooperating with an abutment means. The main object of the invention is to be seen therein that the abutment means comprises a longitudinal border extending into the path of the knives outside the periphery of the roller and an elongated pad situated parallel to the roller axis, this pad being on the side turned towards the roller provided with abutment and sliding surfaces for the knives said surfaces extending in the transverse direction of the pad the knives against their surfaces. When the material web is fed between the knife roller and the abutment pad, the web is pressed by the knives against the abutment and sliding surfaces—in the following denoted quite simply, abutment surfaces—on the pad and causes thereby a transverse perforation which comprises a transverse row of narrow, notchlike openings in the material web situated in the row at a distance from each other which corresponds to the distance between adjacent abutment surfaces on the pad.

According to a preferred embodiment of the invention the abutment surfaces are glass which, against the action of a pneumatic hose, are individually rebounding when hit by the knife. In such a device there is not required any notable precision but the abutment of the knife will always be sufficient and effective also after a considerable wearing of the knife as well as of the glass.

The invention will now be elucidated with reference to the accompanying drawings. In the drawings:

FIG. 1 is an end elevation shown partly in cross section of a perforating machine provided with a perforation device according to the invention.

FIG. 2 shows on an enlarged scale a cross section through the perforation device proper,

FIG. 3 is a side elevation shown in a partial vertical longitudinal section of the right-hand part of the perforating machine, and

FIG. 4 is a plan view of a border piece of a paper web provided with a transverse perforation.

Mounted for rotation between the two vertical stand gables 1 (only one shown on the drawings) is a horizontal roller 2 having rather long knife blades 5 clamped by means of the clamping pieces 4 in longitudinal grooves 3 in the roller 2, said knife blades 5 extending over the whole length of the roller 2 and reaching with a border portion 6 outside the periphery of the roller. Cooperating with the knife roller 2 are two guide rollers 7 covered with soft felt and guiding a paper web 8 from a storage roller (not shown) over the knife roller 2. Extending over the knife roller 2 are two arms 9 which with one end are journaled about a shaft 10 parallel to the knife roller 2. A number of rectangular abutment means 13 of glass are arranged in a downwards opening groove 11 in a bar 12 carried in one of the arms 9, these abutment means in the lower position, the operation position, resting with their ends on supporting ribs 14 along the opening 15 of the groove against the knife roller 2. At the top of the groove 11 there is inserted a bladder or a hose 16 extending along the whole of the groove and comprising an elastic material, e.g. rubber, said hose 16 adapted to be connected to a source of compressed air (not shown). The air pressure in the hose 16 keeps all the abutment means 13 resiliently against the supporting ribs 14. Inserted between adjacent abutment means 13 is a distance piece 17. An adjustment bolt 18 extends through the free end of the arm 9 in question and rests with the lower end on the stand gable 1 and this bolt can be used for adjusting the bar 12 in such a way that the lower border portions 19 of the abutment means will be situated in the path of the outer borders 6 of the knife blades 5 at the rotation of the knife roller 2. A piston 21 which is vertically displaceable in a cylinder 20 can be used for swinging the arms 9 with the bar 12 in counter clockwise direction according to FIG. 1 such that the glass abutment means 13 are lifted out of contact with the knife blades 5 such that the insertion of the paper web 8 over the knife roller 2 is facilitated.

When the paper web 8 at a lowered bar 12 is with a speed, corresponding to the peripheral speed of the knife roller 2, fed through the machine in the direction of the arrow 22 in FIG. 2, the knife blades 5 press with the outer borders 6 the paper web up against the abutment surface 23 of the abutment means 13, the glass abutment means by the knives being somewhat lifted in the groove 11 against the action of the pressure in the hose 16 to allow the knife blade border 6 to slidingly pass over the surface 23. The knife blade border 6 tears at its passing along the abutment surface 23 on the abutment means 13 a narrow slot 24 (FIG. 4) in the paper web 8. This web 8 is hereby provided with the perforation line shown in FIG. 4 comprising slots 24 and therebetween unbroken parts 25 of the paper web 8. The lengths of the slots 24 correspond to the thickness of the glass abutment means 13 and the distance between neighboring slots 24 corresponds to the thickness of the distance pieces 17. The slots 24 in the paper web 8 thus are formed on the one hand by the pressure of the knife blade borders 6 against the glass abutment means 13 and on the other hand by means of a tearing due to the sliding of the blade border 6 along the abutment surfaces 23.

In order to prevent the occurrence of a toothed border 6 on the knives 5 at this wearing as there does not occur any wearing of the border in the interspace 26 between adjacent abutment means 13, the bar 12 is arranged to slide axially in relation to the knife roller 2. According to the embodiment shown in FIG. 3 the bar 12 (or the arms 9) is provided with an elongation arm 27 having a transversely (perpendicularly to the

drawing plane according to FIG. 3) extending and somewhat oblong opening 28, an eccentric tap 29 engaging this opening 28 from below, said tap 29 being driven for rotation. The value of the eccentricity has been denoted by reference letter 30. The eccentric tap 29 is driven via a worm gear 31 from the driving device of the machine (not shown).

At the operation of the machine the bar 12 is, due to the rotating eccentric tap 29, displaced together with the pad of glass abutment means 13 axially in relation to the knife roller 2 at least a distance which equal to the width of the interspaces 26.

Rather than having the bar 12 displaced axially in relation to the knife roller 2, the latter may be arranged to be displaced in relation to the bar 12.

The invention has been described in the foregoing for purposes of illustration only and is not intended to be limited by this description or otherwise except as defined in the appended claims. Thus, the different parts of the perforation machine may be constructively modified in many ways without departure from the inventive idea. Rather than abutment means 13 of glass it could be used such of ceramics and hard metal but due to their extreme hardness, wear resistance and low price glass is probably to be preferred. In order to obtain the required interspaces 26 between the abutment means 13 at the abutment surface 23 there is according to one embodiment of the invention possible to shape the abutment means 13—instead of using distance pieces 17—with bevels in such a way that the side surfaces converge down towards its abutment surface.

Due to the glass abutment means pad which is under pressure from the pneumatic hose 16 and the different glass abutment means 13 in said pad being individually loaded, the perforation device is practically insensible for deflections and vibrations such that the machine may be constructed rather light. The fine adjustment is restricted essentially to the adjustment of the pressure in the hose 16. However, the invention also embraces a pad serving as a grate for the knife blades 5.

said pad comprising different abutment means which are individually pressure loaded in another way. Finally, the invention also embraces a grate pad in which the interspaces 26 between the abutment surfaces 19 have been obtained e.g. by means of milling in a stationary beam or bar of steel or another hard and wear resistant material.

I claim:

1. A machine for transversal perforation of webs of paper or similar material, said machine comprising a rotating knife roller which is provided with at least one knife extending in the longitudinal direction of the roller, said knife adapted for cooperation with an abutment means, wherein the improvement means of a longitudinal border adapted to reach into the movement path of said knife and outside the periphery of the roller, and an elongated pad extending parallel to the roller axis, said pad at the side turned towards the roller provided with a plurality of abutment and sliding surfaces for the knife which are extending in the transverse direction of the pad, said surfaces being separated from one another by separating pieces.

2. A machine for transversal perforation of webs of paper or similar material, said machine comprising a rotating knife roller which is provided with at least one knife extending in the longitudinal direction of the roller, said knife adapted for cooperation with an abutment means, wherein the improvement comprises abutment means of a longitudinal border adapted to reach into the movement path of said knife and outside the periphery of the roller, and an elongated pad extending parallel to the roller axis, said pad at the side turned towards the roller provided with a plurality of abutment and sliding surfaces for the knife which are extending in the transverse direction of the pad, said surfaces being separately bevelled so that they taper towards their abutment border and said surfaces being separated from one another by separation pieces.
